UNITED STATES PATENT OFFICE.

HARRY E. PICKARD, OF TONAWANDA, NEW YORK.

ICE-CREAM-CARTON HOLDER AND FILLER.

1,159,990.

Specification of Letters Patent.

Patented Nov. 9, 1915.

Application filed November 10, 1914. Serial No. 871,368.

To all whom it may concern:

Be it known that I, HARRY E. PICKARD, a citizen of the United States, residing at Tonawanda, in the county of Erie and State 5 of New York, have invented new and useful Improvements in Ice-Cream-Carton Holders and Fillers, of which the following is a specification.

This invention relates to a device for holding ice cream cartons or boxes while the same are being filled or loaded.

The principal object of the invention is to provide a device whereby the box or carton may be held rigidly against distention while 15 it is being filled, thus enabling it to be easily and conveniently handled and filled to its proper capacity without overfilling and loss to the dealer.

A further object of the invention is to provide 20 a box holding device which admits of the ready application and removal of the boxes.

The invention consists of the features of construction, combination and arrangement 25 of parts herein fully described and claimed, reference being had to the accompanying drawings in which:—

Figure 1 is a perspective view showing the holder fully opened to receive a box or carton. Fig. 2 is a similar view taken at right angles to that shown in Fig. 1 and with the holder in the same condition. Fig. 3 is a view in side elevation illustrating the mode of applying and removing a carton. Fig. 4 is a vertical longitudinal section through the 35 filled holder. Fig. 5 is a vertical transverse section thereof. Fig. 6 is a longitudinal section taken on a plane at right angles to the plane of section of Fig. 4. Fig. 7 is a detail of the rim member. Fig. 8 is a sectional view showing a modification.

Referring to the drawings, 1 designates the holder or receptacle, of pyramidal form, and of a size to snugly receive an ice cream 45 box or carton of the usual shape and of any prescribed dimensions. This receptacle comprises a pair of stationary side walls 3, a bottom or back wall 4, to which said walls 3 are fixed at their inner or rear ends, a pair 50 of movable end side walls 5 and a rim frame 6, all of which parts are preferably constructed of galvanized sheet metal. A looped handle 7, preferably made of the same material, is fixed to the bottom or back wall 4, and provides a means whereby the device may be manipulated and transported.

A box 2 which is to be filled or packed with ice cream is first prepared by turning its cover flaps down parallel with its side and end walls, after which it is inserted into 60 the receptacle 1 through one of the open sides or ends thereof, as illustrated clearly in Fig. 3, after which said receptacle is closed so as to hold the box or carton in position by adjusting the movable end walls 5 65 and rim frame 6 to closed positions.

As shown, the walls 5 are hinged or pivoted, as at 8, to the wall 4 and are adapted to be swung rearwardly to open position and to be swung forwardly to close the open 70 sides of the receptacle 1, the said walls 5 being provided with side flanges 9 to overlap the edges of the walls 3, whereby the hinged walls are more firmly sustained and the receptacle closed so as to also prevent disten- 75 tion of the fixed walls 3.

The rim section 6 comprises an open rectangular body or frame which is formed with an inwardly extending flange 10 providing an internal marginal groove or recess to receive and engage the edges of the walls of the box 2, by which the cover flaps of the box will be positively held open and the mouth of the receptacle left unobstructed 80 so that it may be quickly and conveniently 85 filled. The said rim member 6 is adapted to be adjusted in a direction toward and from the wall 4 to engage and release the inserted box and when in box engaging position holds the box clamped against outward displacement, while at the same time the rim member receives and laps over the outer edges of the walls 3 and 5 and thus holds them fixed with 90 relation to each other. By this means the contained box or carton may be packed 95 through the rim member 6 as a mouth without interference from any of its portions, and also without unduly distending the box, so that the proper amount of cream may be packed therein without liability of loss to 100 the dealer, as is liable to occur under ordinary conditions when the box is carelessly packed or filled by an inexperienced hand.

The mouth section or rim member 6 is provided with flange extensions or guide members 11 which overlap the walls 3 and insure a free, easy and positive guiding motion of said rim section when adjusted inwardly and outwardly. These portions 11 of the rim section are carried by yoke arms 12 slidable 105 in guide loops or slits 13 and connected at their inner ends by a cross bar 14 extending 110

in rear of the wall 4. As shown in Figs. 1 to 7, inclusive, a handle or operating device 15 is disposed between the sides of the operating or manipulating handle 7 and fixed at 5 one end to the cross piece 14 and provided at its other end with a finger loop 16, by means of which the yoke as a whole may be adjusted to shift the mouth piece or rim member 6 inwardly and outwardly for the purpose 10 poses described.

It will thus be understood that a receptacle is provided into which a box or carton of the desired size may be slipped and the receptacle then closed and the box clamped 15 to hold the said box in position and also prevent its distention, while permitting the box to be rapidly and conveniently filled, and that therefore by adjusting the parts to open the receptacle the filled box may be 20 readily and conveniently removed.

The device allows a box to be held and filled with accuracy in less than the usual amount of time without liability of loss to the dealer or customer through over or under filling of the box.

It will be further evident that the construction described adapts the box to be at all times thoroughly washed and kept in a clean and sanitary condition.

30 In Fig. 8 I have shown a modified construction wherein an arm 17 is substituted for the operating handle 15, said arm being connected by a link 18 with a lever 19 pivoted to the manipulating handle 7, whereby 35 the mouth piece or rim section may be adjusted, as will be readily understood.

It will also be understood that the device provides means by which a box or carton may be held rigid while it is inserted into 40 a body of ice cream, so that the carton may be filled in a ready and convenient manner.

I claim:

1. A device for holding ice cream boxes while being filled, comprising a receptacle 45 having a lateral opening for the insertion and removal of the box, a hinged wall for closing said opening, a mouth piece adapted to clamp the hinged wall and box in position and provide a filling passage, and 50 means for adjusting said mouth piece into and out of engaging position.

2. A device for holding ice cream boxes while being filled, comprising a receptacle having a pair of fixed walls and a pair of 55 hinged walls, a handle carried by said receptacle, a mouth or rim portion adjustable into and out of engagement with said walls and the rim edges of the box, and means for adjusting said mouth piece.

3. A device for holding boxes of ice cream 60 while being filled, comprising a receptacle having a side opening, a closure therefor, an adjustable mouth piece to engage the walls of the receptacle and box and maintain the same in fixed relation, and means for adjusting said mouth piece into and out of engaging position.

4. A device for holding ice cream boxes while being filled comprising a receptacle having an open side, a closure for said open 70 side, a handle carried by said receptacle, a mouth piece adjustable to engage the walls of the receptacle and closure and maintain the same in relative position, and having an internal groove or recess to receive and engage the rim edges of the box, and means for adjusting said mouth piece into and out of engaging position.

5. A device for holding ice cream boxes while being filled, comprising a receptacle 80 open at opposite sides, hinged walls for closing said open sides, a mouth piece adjustable into and out of engagement with the walls of the receptacle and the box disposed therein, a handle carried by said 85 receptacle, and means for adjusting said mouth piece into and out of engaging position.

6. A device for holding ice cream boxes while being filled comprising a receptacle 90 including a bottom, a pair of fixed side walls and a pair of hinged side walls, the latter having flanges to lap said fixed walls, a mouth piece comprising an open frame adapted to lap over the outer edges of said 95 walls and having an internal groove or recess to receive and engage the rim edges of the walls of an inclosed receptacle, a handle carried by the receptacle, and means for adjusting said mouth piece into and out of engaging position.

7. A device for holding ice cream boxes while being filled, comprising a receptacle having a bottom wall, two fixed side walls, and two hinged side walls, a looped handle 105 connected with the bottom wall, guide members upon the fixed side walls, an adjustable mouth piece, a yoke connected with the mouth piece and in guided engagement with said handle and guide members, and means 110 for reciprocating the yoke.

In testimony whereof I affix my signature in presence of two witnesses.

HARRY E. PICKARD.
